GAS COMPRESSOR

Carl A. Bergmann, Milwaukee, Wis., assignor to
Walter D. Mann, Milwaukee, Wis.

Application August 2, 1933, Serial No. 683,332
Renewed April 15, 1935

20 Claims. (Cl. 230—108)

The present invention relates in general to improvements in the art of compressing gases, and relates more specifically to improved apparatus for compressing air or other elastic fluids with the aid of centrifugal force acting upon a carrier liquid.

Generally defined, an object of the invention is to provide improved apparatus for producing high compression of gases in a substantially isothermal manner and with maximum efficiency.

While it has heretofore been proposed to utilize an ordinary centrifugal pump for the purpose of hydraulically compressing air to some extent, by mixing the air with the liquid passing through the pump rotor and by subsequently separating the air from the mixture expelled by the rotor, this method of compression is relatively inefficient and is not adapted for high compression of the gas.

It is a more specific object of the present invention to provide an improved rotary hydraulic compressor for elastic fluids such as air, wherein any desired degree of compression of the gas may be obtained with minimum expenditure of power, by utilizing centrifugal force to compress the fluid while mixed with liquid, and by additionally utilizing the pressure acting upon the separated liquid to regain the energy which is substantially wasted when utilizing the ordinary centrifugal pump for air compression purposes.

Another specific object of the invention is to provide a rotary hydraulic air compressor of relatively simple and compact construction adapted to produce substantially isothermal compression of gas to relatively high pressures in a single stage.

A further specific object of the invention is to provide an improved rotary gas compressor which is relatively devoid of leakage and friction losses, and which is especially adapted for use in connection with refrigeration systems and in conjunction with rotary motors such as gas turbines.

Still another specific object of the invention is to provide an improved high compression rotary gas compressor which is entirely automatic and continuous in its operation, and wherein the fluent compressing media is repeatedly re-utilized and retained at desired temperature.

Another specific object of the invention is to provide a simple rotary hydraulic compressor which is adapted to effectively simultaneously compress several different kinds of elastic fluid, and wherein centripetal force acting upon the gas carrier is utilized to enhance the compression.

These and other objects and advantages will be apparent from the following detailed description.

A clear conception of several embodiments and adaptations of the invention, and of the mode of constructing and of operating rotary hydraulic compressors in order to carry on the improved method, may be had by referring to the drawings accompanying and forming a part of this specification in which like reference characters designate the same or similar parts in the various views.

Fig. 1 is a somewhat diagrammatic central longitudinal section through one form of the improved rotary hydraulic air compressor and through the control mechanism thereof;

Fig. 2 is a transverse section through the rotor of the compressor of Fig. 1, the section having been taken along the line 2—2;

Fig. 3 is an enlarged fragmentary circumferential section through the liquid discharge portion of the rotor of Fig. 1, taken along the line 3—3;

Fig. 4 is a central longitudinal section through a modified form of structure for admitting the gas and for mixing the same with the liquid compressing medium to initially compress the gas before entering the rotor;

Fig. 5 is a central longitudinal section through a fragment of a modified rotor adapted to simultaneously compress segregated charges of the same or different kinds of gas;

Fig. 6 is a diagrammatic central longitudinal section through a further modified form of rotor embodying a different type of energy regaining apparatus cooperating with the separated gas carrier liquid;

Fig. 7 is a diagrammatic transverse section taken centrally through the modified rotor of Fig. 6; and

Fig. 8 is a relatively diagrammatic elevation of a rotor of Figs. 6 and 7, showing a velocity diagram of the discharged gas carrier liquid.

Referring specifically to Figs. 1, 2 and 3, the improved gas compressor therein disclosed, comprises in general a frame 18, a casing 19 cooperating with the frame 18 to provide a sealed chamber, a rotor 20 disposed within the chamber, a shaft 21 to one end of which the rotor 20 is attached, a bearing housing 22 secured to the frame 18 and rotatably supporting the shaft 21, and a pulley 23 or equivalent means for imparting rotation to the shaft 21 and rotor 20.

The rotor 20 is provided with a series of substantially radial compression conduits 24 having

their inlet ends disposed closely adjacent to the rotor axis and in open communication with a normally fixed supply nozzle 25, a series of separating conduits 26 extending laterally away from the outer ends of the adjoining compression conduits 24, and a series of decelerating substantially radial return conduits 27 the outer ends of which communicate with the adjacent separating conduits 26 and the inner ends of which communicate with passages in a stationary liquid return casing 28 at points spaced greater distances from the rotor axis than the inlet ends of the compression conduits 24. This construction provides compression conduits 24 which are of greater radial length than the corresponding return conduits 27, and the passages in the return casing 28 are formed to deliver the returned liquid centrally into the nozzle 25, thus completing the liquid circuits within the compressor. The liquid return casing 28 supports an air or other gas supply housing having a central inlet opening controlled by a non-return check valve 29, and gas admission ducts 30 connect the supply housing with the space within the normally fixed nozzle 25. The nozzle 25 is constantly urged along the rotor axis and into sealing engagement with an annular abutment on the return casing 28, by one or more springs 31 but may be moved in opposition to the spring by gas under pressure, and the peripheral portion of the rotor 20 is provided with annular gas collecting grooves 32 which communicate with all of the separating conduits 26 on both sides of the radial conduits 24, 27.

Compressed gas discharge ducts 33, formed within the rotor 20, have their outer ends communicable with the grooves 32 and controllable by means of valves 34 which are operable by floats 35, and the inner ends of the ducts 33 are in open communication with one end of a central gas discharge passage 36 formed in the rotor shaft 21. The opposite end of the passage 36 is connected to a chamber 37 through radial holes in the shaft 21, the chamber 37 being disposed adjacent to anti-friction bearings 38 carried within the housing 22 and coaxing with the shaft 21. The ends of the chamber 37 are sealed by packings 39, and a discharge pipe 40 connects this chamber with another chamber 41 in one end of a tank 42, a non-return check valve 43 being interposed between the chamber 37 and the pipe 40. The tank chamber 41 is provided with a final compressed gas outlet having a pressure retaining discharge valve 44 therein, and is also provided with a safety pressure-relief valve 45. A pipe 46 connects the tank chamber 41 with a port in the liquid return casing 28 adjacent to the end flange of the nozzle 25, and a control valve 47 is interposed in the pipe 46 for the purpose of regulating the axial movement of the nozzle 25 in opposition to the spring 31. The valve 47 is operable by the fluid pressure from within the chamber 41 acting upon a plunger 48 in opposition to a spring 49, and has a pressure relief port 50 which connects the nozzle 25 with the atmosphere when the pressure within the chamber 41 is abnormally low. As the pressure within the chamber 41 reaches its maximum, the pressure acting upon the plunger 48 will position control valve 47 to permit gas under pressure to flow through the pipe 46 to the duct adjoining the actuating flange of the inlet nozzle 25, and the nozzle is subjected to pressure sufficient to overcome the pressure exerted by the spring 31, and the nozzle is shifted to the right as viewed in Fig. 1 to thereby throttle the inlet to the compression conduits 24.

The tank 42 is also provided with a liquid storage reservoir 51 having a float actuated valve 52 which discharges the excess liquid accumulating during operation of the compressor, and a drain cock 53 associated with the lower portion thereof, and a screen or filter wall 54 segregates these elements from the outlet pipe 55 which leads from the reservoir 51 to the compressor rotor inlet. The chamber formed by the frame 18 and casing 19, and surrounding the rotor 20, is connected to the interior of the reservoir 51 in line with the inlet of the pipe 55, by a pipe 56, thus creating an ejector effect and establishing a partial vacuum around the exterior of the rotor 20. A branch pipe 57 connects a medial portion of the 15 vacuum producing pipe 56 with a sealing chamber 58 surrounding the hub of the rotor 20, thus expelling leakage liquid which may escape from the rotor inlet passages, before it enters the space surrounding the rotor. The reservoir 51 is also 20 provided with a safety valve 58' which is set at a comparatively low pressure, just sufficient to force the water into the rotor for priming purposes, and to maintain the circulation of the cooling water, an air pump 59, and with a liquid intake valve 60, and is of sufficient capacity to hold all of the liquid normally filling the rotor and sufficient excess to insure proper operation of the system.

The liquid return passage within the return 30 casing 28 is connected by means of a pipe 61 to the upper portion of a radiator 62, the radiating tubes of which are disposed around the bearing housing 22, and the lower portion of the radiator communicates through a pipe 63 with the reservoir 51 in advance of a baffle wall 64 as shown in Fig. 1. The capacity of the pipe 61 is relatively limited, and the heated liquid withdrawn by this pipe, is cooled in the radiator and flows through the pipe 63 to the reservoir 51 by gravity and due 40 to the kinetic energy of the liquid in the return casing 28. In order to enhance the cooling effect, the radiator 62 may be subjected to a circulation of air from a fan 65 mounted upon the shaft 21 within a conduit 66 carried by the radiator, and 45 the fan 65 cooperates with a centrifugal governor 66' which in turn coacts with a slide valve 67 to cut off communication between the high pressure gas chamber 41 and the reservoir 51 when the unit is at rest. The valve 67 is interposed 50 between ducts 68, 69, the former of which communicates with the chamber 41 and the latter of which leads to a diaphragm actuated slide valve 70, and another duct 71 connects the valve 70 directly with the upper portion of the reservoir 55 51. The valve 70 is operable by a diaphragm 72, one side of which is exposed to the pressure in the reservoir 51 through a pipe 73, and the opposite side of which is connected to the return passage within the casing 28, by a pipe 74, so that 60 if the pressures in the reservoir are sufficient to force the liquid into the compressor, the valve 70 will be shifted to cut off communication between the ducts 69, 71.

During normal operation of the improved rotary compressor shown in Figs. 1, 2 and 3, rotary motion is imparted to the rotor 20 with the aid of the pulley 23 attached to the shaft 21, and the liquid within the rotor 20 and casing 28 is being constantly circulated through the conduits 24, 26, 70 71 at velocities dependent upon the speed of revolution of the rotor. As this liquid passes through the stationary return passages in the casing 28 and flows through the relatively fixed nozzle 25, air or other gas is entrained through the ducts 30, 75

and past the valve 29, and is mixed with the liquid in the form of bubbles as shown in Figs. 1 and 2. In passing outwardly through the compression conduits 24, the columns of mixture are subjected to progressively increasing centrifugal force, and when the separating conduits 26 are reached the air or gas under high pressure is expelled from the liquid by the continued action of centrifugal force thereon, and enters the annular passages 32 from whence it flows through the passages 33, 36 into the chamber 37 and eventually escapes to the chamber 41 through the pipe 40. The separated liquid flows into the return conduits 27 by virtue of the lesser head of liquid in these conduits and the resultant decreased centrifugal force acting upon the return columns, and the difference in head of the columns in the conduits 24 and 27 is sufficient to overcome the friction of the liquid flowing through the rotor. The pressure and the peripheral speed of the particles of the liquid are reduced while they return through conduits 27. The kinetic energy of the liquid which is consumed by the particles of the liquid passing through conduits 24 where they gradually reach the maximum peripheral speed in the conduits 26, is returned in conduits 27. It is evident that the circulating liquid does not consume any power, because the wall pressures which accelerate and decelerate the liquid while flowing through the rotor cancel each other.

The liquid conduits 27 within the rotor hub adjacent to the casing 28 are preferably formed as shown in Fig. 3, in order to reduce the absolute speed of the returning liquid in the casing 28, to approximately the intake speed of the liquid in the rotor, and to eliminate eddy currents. The degree of compression is obviously dependent upon the speed of the rotor 20, and the compressed gas may be withdrawn from the chamber 41 past the discharge valve 44.

The heat generated during the compression of the gas, is quickly absorbed by the carrier liquid thereby maintaining the compression substantially isothermal. Due to the absorption of the heat of compression by the liquid, this liquid upon entering the passages within the casing 28 will be heated, and in order to maintain the carrier liquid at substantially uniform temperature, a portion thereof is permitted to pass into the radiator 62 through the pipe 61. The revolving fan 65 cools the liquid entering the radiator 62, and this cool liquid is subsequently delivered to the reservoir 51 from whence it is eventually returned to the casing 28 where it is mixed with the warmer return liquid passing into the nozzle 25. The radiator 62 may obviously be utilized for heating purposes, in large compressors where the volume of liquid is sufficient to warrant such use, thus conserving the heat for useful purposes. The liquid returned through the pipe 55, besides cooling the liquid within the rotor 22, also sets up an ejector action which produces a partial vacuum within the casing 19 and surrounding the rotor, thereby reducing to a minimum the friction losses; and if so desired, the fan 65 may be omitted thus further reducing the power required to drive the compressor.

If the pressure within the chamber 41 accidentally becomes excessive, the safety valve 45 will function to automatically release the excess pressure. When the compressor is at rest the valve 47 will be shifted by the spring 49, to bring the duct adjoining the actuating flange of the inlet nozzle 25 into communication with the atmosphere through the port 50, and the spring 31 will

shift the inlet nozzle 25 to the left. Another spring will shift the slide valve 70 so as to connect the duct 69 with the duct 71. The centrifugal governor 66' will be at rest, thereby causing the slide valve 67 to disconnect the duct 69 with the chamber 41 through the duct 68, so that leakage is prevented from the chamber 41, and a slight pressure is always retained within this chamber by valve 44 for priming purposes, after the compressor has once been operated.

In order to prime the unit when the compressor is started, the pump 59 may be operated to establish sufficient pressure within the reservoir 51 above the liquid therein, to properly fill the rotor conduits 24, 26, 27 through the pipe 55. The floats 35 coacting with the valves 34, will maintain the ducts 33 sealed until gas under pressure lodges in the gas passages 32, whereupon these floats 35 will ride upon the liquid flowing through the conduits 26 within which these floats are disposed. After the compressor has once been started due to the rotation of the rotor 20 and shaft 21, the governor 66' will open valve 67, thus allowing gas to escape from within the reservoir 41 through slide valve 70 into the reservoir 51. This gas presses on the liquid in the reservoir 51 and forces this liquid into the compressor which is thus primed; and after the rotor has once been primed, the entire operation and control is automatic. The periphery of the rotor 20 may also be provided with automatic drain plugs as shown in Fig. 2, in order to permit removal of all liquid from the rotor so as to prevent possible freezing when the machine is idle.

Referring specifically to Fig. 4, the mixture supply nozzle 75 of this modification, differs from the nozzle 25 of Figs. 1, 2 and 3, in that it is formed integral with the liquid return casing 76 and has an expanding or enlarging cross-section in the direction of flow of the gas and liquid mixture. The rotor 20 is of the same construction as previously described, and the operation of this modified machine is similar to that previously described, with the exception that the gas is pre-compressed as it passes through the expanding nozzles 75, where velocity energy of the mixture is changed into pressure energy, thus making possible a higher ratio of gas to liquid for the mixture. This structure is also simpler than that previously described, by virtue of the integral construction of the nozzle 75 and return casing 76.

Referring specifically to the double rotor structure of Fig. 5, this construction is more especially adapted for machines of larger capacities, or in machines wherein it is desired to simultaneously compress segregated charges of different kinds of gas which are to be ultimately mixed with each other. In this machine, the rotor 77 is provided with two sets of substantially radial compression conduits 78, and with two sets of cooperating liquid return conduits 79, and with intervening axially extending separating conduits 80 connecting the outer ends of the corresponding compression and return conduits 78, 65 79. All of the annular separating conduits 80 of each set, communicate with an annular compressed gas collecting duct 81, and the ducts 80 insure a perfect balancing of the rotor. In case one compression conduit discharges more liquid than the other conduits, the annular level of the liquid is quickly equalized by the centrifugal force and the balance of the rotor is not destroyed. The ducts 81 communicate with a common gas discharge passage 82 which connects with a dis- 75

charge conduit 83 located centrally within the rotor supporting shaft 84. The other accessories associated with this modified double rotor, are substantially the same as previously described, and the operation of this double compressor should be apparent from the foregoing description. While the axial disposition of the liquid separating conduits 80, somewhat increases the width of the rotor, over the previously described circumferential arrangement thereof, this axial arrangement will permit more compact disposition of the other conduits 78, 79 and is therefore especially suitable for a double compression machine.

Referring specifically to the machine illustrated in Figs. 6 to 8 inclusive, this compressor differs from those previously described, in the mode of regaining the energy of the carrier liquid after the compressed gas has been liberated. The rotor 85 is supported by a shaft 86 and is provided with substantially radial compression conduits 87 the inner ends of which communicate with a gas and liquid supply nozzle 88, and the outer ends of which are connected to an annular liquid separating conduit 89 communicating with an annular compressed air collecting passage 90. The rotor 85 is housed within a sealed casing 91 having a liquid storage reservoir 92 therebeneath and communicating with the space within the casing 91 surrounding the rotor, through ports 93. The lower end of the nozzle 88 is in open communication with the reservoir 92 beneath the level of the liquid therein, and the gas to be compressed is supplied to the nozzle 88 by ducts 94, while the compressed gas is discharged from the passage 90 through ducts 95, 96 and a final discharge pipe 97. In this modified machine, the return of the separated carrier liquid is effected by delivering the same from the separating duct 89 through tangential nozzles 98, and the reaction of the jets of liquid delivered at high velocity from the nozzles 98 during rotation of the rotor 85, serves to simultaneously diffuse the pressure on the carrier liquid so as to augment the compression of the compressed gas, and to assist in driving the rotor 85, thereby reducing the energy losses to a minimum. The relative speed W of the liquid is nearly opposed to the peripheral speed U of the rotor and is only slightly smaller than speed U , so that the energy is negligible in the liquid which leaves the rotor with the small absolute velocity C . The liquid is discharged by the nozzles 98 through the ports 93 and creates a partial vacuum in the space within the casing 91 due to the ejector action of the jets. In this machine, as in those previously described, the compression is effected by centrifugal force acting upon the liquid columns within the conduits 87, and the separation of the liquid and gas is likewise effected by centrifugal force within the same rotor.

From the foregoing description of the various modifications, it will be apparent that the invention provides a simple, compact and highly efficient gas compressor wherein the actual compression and separation of the gases under pressure is effected with the aid of centrifugal force within a single rotor. The deceleration or diffusion of the carrier liquid is utilized in various ways to augment the gas compression, and the compressed gas is always delivered from the machine in relatively dry condition. The compression is substantially isothermal, and minimum power is required by operating the compressor

rotor in a partial vacuum. The heat resulting from the compression may also be utilized for heating or other purposes, thereby reducing the energy losses to a minimum, and the improved method has proven highly satisfactory in actual use.

It should be understood that it is not desired to limit the invention to the exact details of construction and operation herein shown and described, for various modifications within the scope of the claims may occur to persons skilled in the art.

It is claimed and desired to secure by Letters Patent:—

1. In a compressor, a rotor having a compression conduit extending away from the rotor axis, means for delivering a mixture of liquid and gas to the inner end portion of said conduit, means for removing compressed gas from said rotor near the other end of said conduit, means associated with said rotor for decelerating the flow of the separated liquid and for causing deceleration to augment the compression of the gas, and means operable by the generated pressure for controlling both the maximum and the minimum pressures obtainable.

2. In a compressor, a rotor having therein a compression conduit extending away from the rotor axis, means for delivering a mixture of liquid and gas into a portion of said conduit adjacent said axis, means for causing the mixture to travel within said rotor and laterally of said conduit near the outer end thereof to separate the compressed gas from the liquid, means for decelerating the flow of the separated liquid within said rotor to augment the pressure of the removed gas, means for automatically controlling the maximum pressure obtainable, and means for automatically controlling the minimum pressure obtainable.

3. In a compressor, a rotor having therein a compression conduit extending away from the rotor axis, means for delivering a mixture of liquid and gas into a portion of said conduit adjacent said axis, means for causing the mixture to travel within said rotor and laterally of said conduit near the outer end thereof to separate the compressed gas from the liquid, means for decelerating the flow of the separated liquid within said rotor to augment the pressure of the removed gas, means for directly returning the diffused liquid to the inlet portion of said conduit, and a non-return check valve associated with said liquid return means for permitting ingress of liquid while preventing escape of liquid.

4. In a compressor, a rotor having therein segregated substantially radial compression and return conduits connected by a conduit all portions of which are disposed substantially equidistant from the rotor axis, means for admitting a mixture of gas and liquid to the end of said compression conduit adjacent the rotor axis, means including a float controlled valve for effecting removal of compressed gas from the side of said connecting conduit nearest said axis, and means for returning liquid from the end of said return conduit adjacent said axis to the corresponding end of said compression conduit.

5. In a compressor, a rotor having therein an outwardly directed compression conduit and an inwardly directed return conduit of less length than said compression conduit, means for admitting mixed gas and liquid to the inner end of said compression conduit, means for removing

- compressed gas from the outer end of said compression conduit and for delivering the separated liquid into the outer end of said return conduit, means for delivering said liquid from the opposite end of said return conduit into the corresponding end of said compression conduit together with other gas, and means for automatically discharging excess liquid from the compression and return passages.
5. In a compressor, a rotor having therein a conduit for receiving a mixture of liquid and gas and for utilizing centrifugal force to compress the gas, float controlled means for effecting discharge of compressed gas from said conduit, a housing for said rotor, and means for utilizing the action of one of the fluids to maintain the interior of said housing under reduced pressure.
10. In a compressor, a rotor having therein a conduit for receiving a mixture of liquid and gas and for utilizing centrifugal force to compress the gas, a casing forming a chamber surrounding said rotor, and means for utilizing the action of one of the fluids to maintain said chamber under a partial vacuum.
15. In a compressor, a rotor having therein an outwardly directed conduit for compressing gas mixed with liquid flowing outwardly through said conduit, means forming a gradually expanding passage for admitting the liquid to the inner end portion of said conduit, means for introducing gas into said passage in pre-compressed condition, and means for pre-cooling the liquid circulated through said passage.
20. In a compressor, a rotor having therein a plurality of compression conduits extending away from the rotor axis, means for delivering a mixture of liquid and gas in pre-cooled condition to the inner end portion of each of said conduits, float controlled means for removing compressed gas near the outer end of each of said conduits, and independent means associated with said rotor for decelerating the flow of the separated liquid discharged from each of said conduits.
25. In a compressor, a rotor having therein a plurality of compression conduits extending away from the rotor axis, means for delivering mixed gas and liquid into the inner end portion of each of said conduits, means forming separating conduits within said rotor extending along the axis thereof and away from the outer ends of said compression conduits, means for independently conducting gas and liquid away from said separating conduits, a liquid supply reservoir, and means for pneumatically delivering liquid from said reservoir to said rotor for priming purposes.
30. In a compressor, a rotor having therein a compression conduit extending away from the rotor axis, means for delivering mixed gas and liquid into the end portion of said conduit adjacent to said axis, means forming a separating conduit extending around said axis, and means for discharging the separated liquid from said rotor into the ambient atmosphere tangentially of the rotor periphery.
35. In a compressor, a rotor having a compression conduit extending away from the rotor axis, means for delivering a mixture of liquid and gas to the inner end portion of said conduit, means for removing compressed gas from said rotor near the outer end of said conduit, means associated with said rotor for decelerating the flow of the separated liquid and for causing said deceleration to augment the compression of the gas, and means for releasing excess gas pressure from within said
- rotor and for preventing accumulation of excess gas in said gas removing means.
13. In a compressor, a rotor having a compression conduit extending away from the rotor axis, means for delivering a mixture of liquid and gas to the inner end portion of said conduit, means for removing compressed gas from said rotor near the other end of said conduit, and a safety valve for releasing excess pressure and for preventing accumulation of excess air in said gas removing means.
14. In a compressor, a rotor having therein a plurality of compression conduits extending away from the rotor axis, means for delivering mixed gas and liquid into the inner end portion of each of said conduits, means forming separating conduits within said rotor for removing the gas from the liquid in said mixture, means for independently conducting gas and liquid away from said separating conduits, a reservoir for receiving gas from said rotor, and means for utilizing the pressure of the gas within said reservoir for priming said rotor.
15. In a compressor, a rotor having therein a plurality of compression conduits extending away from the rotor axis, means for delivering mixed gas and liquid into the inner end portion of each of said conduits, means forming a common separating conduit within said rotor communicating with the outer ends of all of said compression conduits, and means for independently conducting gas and liquid away from said separating conduit.
16. In a compressor, a rotor having therein a plurality of compression conduits extending away from the rotor axis, means for delivering mixed gas and liquid into the inner end portion of each of said conduits, means forming a common separating conduit within said rotor communicating with the outer ends of all of said compression conduits, means for independently conducting gas and liquid away from said separating conduit, and common means for removing liquid from all of said conduits and from said liquid conducting means.
17. In a compressor, a rotor having therein a plurality of compression conduits extending away from the rotor axis, means for delivering mixed gas and liquid into the inner end portion of each of said conduits, means forming a common separating conduit within said rotor communicating with the outer ends of all of said compression conduits, means for independently conducting gas and liquid away from said separating conduit, and float actuated means for controlling the delivery of gas from said separating conduit to said gas conducting means.
18. In a compressor, a rotor having therein a compression conduit extending outwardly away from the rotor axis, means for delivering mixed gas and liquid into the end portion of said conduit adjacent to said axis, means forming a separating conduit extending from the outer end of said compression conduit around said axis, means for conducting compressed gas from said separating conduit toward the axis of said rotor, and means for freely discharging the separated liquid from said rotor into the ambient atmosphere tangentially of the rotor periphery.
19. In a compressor, a rotor having therein an outwardly directed conduit for compressing gas mixed with liquid flowing outwardly through said conduit, means forming a gradually expanding passage for admitting the liquid directly to the inner end portion of the conduit, means

for introducing gas into said passage in pre-compressed condition, and means for varying the point of admission of said gas with respect to said expanding passage.

5 20. In a compressor, a rotor having an outwardly directed compression conduit, means for delivering a mixture of liquid and gas to the inner

end portion of said conduit, float controlled means for removing compressed gas from the liquid near the outer end of said conduit, and means for returning the separated liquid to the inner end of said compression conduit together with additional gas to be compressed. 5

CARL A. BERGMANN.
